UNITED STATES PATENT OFFICE

112,297

DESIGN FOR A TEXTILE FABRIC OR SIMILAR ARTICLE

Marris R. Turner, Cleveland Heights, Ohio

Application June 3, 1938, Serial No. 77,548

Term of patent 7 years

To all whom it may concern:

Be it known that I, Marris R. Turner, a citizen of the United States, residing at 2197 Maplewood Avenue, in the city of Cleveland Heights, county of Cuyahoga, and State of Ohio, have invented a new, original, and ornamental Design for a Textile Fabric or Similar Article, of which the following is a specification, reference being had to the accompanying drawing, forming a part thereof.

The figure is an illustration of a textile fabric having the design.

I claim:

The ornamental design for a textile fabric or similar article, substantially as shown.

MARRIS R. TURNER.
